UNITED STATES PATENT OFFICE.

ALONZO G. SHARP, OF COLUMBUS, OHIO, ASSIGNOR TO THE E. M. HULSE COMPANY, OF COLUMBUS, OHIO, A CORPORATION OF OHIO.

SOFA OR DAVENPORT BED.

1,076,843.

Specification of Letters Patent. Patented Oct. 28, 1913.

Application filed July 31, 1911. Serial No. 641,404.

To all whom it may concern:

Be it known that I, ALONZO G. SHARP, a citizen of the United States, residing at Columbus, in the county of Franklin and 5 State of Ohio, have invented a certain new and useful Improvement in Sofa or Davenport Beds, of which the following is a specification.

The object of this invention is to provide 10 an improved construction of sofa or davenport bed in which the parts are of simple and economical construction and easy operation.

The invention is embodied in the construction and combination of parts set forth 15 in the following description and pointed out in the appended claims.

In the accompanying drawing forming part hereof Figure 1 is a view of the bed in side elevation with parts in section showing 20 the mechanism at one end of the bed, the latter being in open or extended position. Fig. 2 is a similar view with the bed folded or closed. Fig. 3 is a top plan view showing the bed and the frame in which it is 25 directly mounted. Fig. 4 is a detail showing the drop leg for the outer bed section. Fig. 5 is a detail in side view of the rocking frame or standard. Fig. 6 is a detail illustrating the form of a slot in the outer section 30 of the spring bed frame.

In the views 10 designates a rectangular box or frame that is bolted at 10^a to usual ornamental end pieces 11. The forward part of this box constitutes the front rail of 35 the structure or the base of the front rail. The character 12 designates the seat frame which is also of rectangular form and suitably upholstered at one side. The seat frame 12 is hinged to the forward edge of 40 the box 10 as indicated at 12^a. The spring bed frame is foldable and comprises an inner section 13, an outer section 14 and a middle section 15 hinged to the sections 13 and 14. The spring bed frame is mounted 45 or supported on the box frame 10, and on the under side of the seat frame 12, so that by manipulating the seat frame only the spring bed can be opened and closed, the bed being normally housed beneath the seat 50 when closed. The mechanism for automatically effecting the opening and closing of

the spring bed frame is the same at each end of the structure so that a description of one will suffice for both. Said mechanism as it appears at one end of the structure will now 55 be described.

Connecting the inner bed section 13 with the box frame 10 is a long bar 16 and a short bar 17. These two bars are hinged together at 17^a and to the bed section 13 and box 10 60 respectively. These bars 16 and 17 serve to support the said bed section at the proper level at the rear end when the bed is opened. Springs 18 connect the rear of the said bed section with the back or end connecting 65 pieces of the structure and serve to hold the said bed section up off the floor when the bed is turned in or closed. These springs 18 are stretched when the bed is closed and because of this they also assist in raising the 70 bed when it is opened.

Journalized in ears 19 and 19^a, at each forward corner of the box frame 10 or on the front rail is a rocking frame or standard 20 that is hingedly connected at its upper end 75 to the middle or connecting section 15 of the bed. This rocking standard 20 has rigidly secured to it an arm 21 and connecting the arm 21 with the seat frame 12 is a link 22 hingedly connected with the seat 80 frame. The link 22 where it receives the pin 21^a of the arm 21 is slotted as seen at 22^a, and the front rail of the box frame is provided with a stop 19^b near the ear 19 against which the standard 20 rests and is wholly 85 supported when the bed is turned to open position best depicted in Fig. 1.

The end of the outer bed-frame section 14 is provided with a slot 23 that has in its upper wall (viewed when the section is 90 open) a notch 23^a. Pivoted on said section to lie close to and parallel with said slot 23 is a catch 28 having a slot corresponding to the slot 23 except that it is enlarged at the inner portion, see Fig. 1, to form a shoulder 95 28^a. Connecting the said bed section and the seat frame is an arm 24 hinged on a pin at 24^b to the seat frame and having a pin 24^a that extends through the aforesaid slot 23 as well as the slot of the catch 28. The 100 arm 24 is provided with a short rigid arm 24^c and connecting said arm 24^c with the

seat frame is a coiled spring 25 that tends when the bed is opened to hold the pin 24^a up in the notch 23^a, it being observed that in this position of the parts the spring 25 lies in a plane above that of the hinge pins 24^b. Upon lifting the seat to close the bed the spring 25 assumes a position below the hinge pin 24^b and the pin 24^a is therefore drawn out of the notch 23^a thus permitting 5 the section 14 to fall onto the seat frame, but in the outward travel of the pin 24^a in the slot 23 said pin 24^a is caught by the shoulder 28^a and the seat and section held fixed with reference to each other until the two 10 are turned into the closed position of the bed. When the seat is lifted outward to open the bed the pin 24^a is free to move in the slots of the dog and bed section beyond the shoulder 28^a because the dog 28 is held 15 downward by gravity so that the two slots are parallel to each other (see Fig. 2). When the bed is opened the edge of the seat is supported by means of legs like that shown at 26. This leg is pivoted to a plate 20 at 26^a and is automatically operated by a link 27 that is hinged to the front bar of the bed section 14 and connected hingedly and eccentrically with the leg at 27^a. When the bed is opened the separation of the bed section 25 25 and the seat frame causes the leg 26 to assume an erect position, and conversely when the bed section 14 closes against the seat frame as before described the leg is thrown up alongside of said frame. 30 The operation is very simple. To open the bed the seat is taken at its free edge by the usual strap, as appears in Figs. 1 and 2, and turned out to the position indicated in Fig. 1. To close the bed the seat is turned inward 35 from the position shown in Fig. 1 until it assumes the position shown in Fig. 2. In these manipulations the parts assume substantially the positions illustrated as the opened and closed positions respectively in 40 Figs. 1 and 2. The rocking standards 20 permit the extension of the spring bed frame with great ease and permit of ample outward projection of the bed when opened. The room provided for the mattress and bed 45 clothing between the bed frame sections is ample and such articles in reasonable bulk do not interfere with the operation of the mechanism. In this construction it will be observed that all the operating mechanism 50 is mounted upon the box frame 10 and seat 12, hence the bed can be shipped unmounted and is easily assembled by the retail dealer. When so mounted it makes a rigid structure. 55 Of course, the back may be provided with a suitable top rail and with a suitable upholstered frame as well understood by those skilled in the art.

What I claim is:

1. In a sofa or davenport bed the combination with a stationary box frame and a

seat frame hinged to the forward portion thereof, of a folding spring bed frame including a middle section, rocking standards journaled directly on the box frame and connected with said middle section, means to limit the outward movement of said rocking standards and means connected with the seat for operating said standards when the seat frame is turned outward from closed position, substantially as described. 70

2. In a sofa or davenport bed, the combination with a box frame and a seat frame hinged to the forward portion thereof, of a folding spring bed frame including an inner section, a middle section and an outer section, rocking standards journaled on the box frame and connected with said middle section, means for supporting the outer section of said folding spring bed frame consisting of bars having a hinged connection with the seat frame and a sliding connection with said outer section and means to limit the movement of the parts in said connection, and springs operative on said bars to hold them at the limits of their movements and to release them from said limits during the operation of the seat frame, substantially as described. 80

3. In a sofa or davenport bed the combination with a box frame and a seat frame hinged to the forward portion thereof, of a folding spring bed frame including an inner, a middle and an outer section, rocking standards journaled on the box frame and connected with said middle section, means for supporting the outer bed section comprising arms hinged to the seat frame, and means for causing said outer section to fall toward the seat frame when the latter is raised from open position, substantially as 90 described. 95

4. In a sofa or davenport bed, the combination with a box frame and a seat frame hinged to the forward portion thereof, of a folding spring bed frame including an inner, a middle and an outer section, rocking standards journaled in the box frame and connected with said middle section, means for supporting the outer bed section comprising arms hinged to the seat frame, and means 100 for causing said outer section to fall toward the seat frame comprising springs adapted to operate to draw said rods in opposite directions during the raising of the seat, and movable catches to limit the movement of 110 the rods with reference to the bed section when the seat is raised from open position, substantially as set forth. 115

5. In a sofa or davenport bed the combination with a box frame and a seat frame hinged to the forward portion thereof, a folding spring bed frame including an inner, a middle and an outer section, rocking standards journaled on the box frame and connected with said middle section, means 125

1,076,843

for supporting the outer bed section comprising arms hinged to the seat frame, means for causing said outer section to fall toward the seat frame when the latter is raised from open position, drop legs on said seat and means connecting the same with the outer section of the spring bed frame op- erated to operate the legs by the falling of said outer spring bed frame toward the seat frame, substantially as described.
